UNITED STATES PATENT OFFICE.

GEORGE W. TINSLEY AND EBENEZER W. STORER, OF MINNEAPOLIS, MINN.

IMPROVEMENT IN MOLDS FOR FINGER-RINGS.

Specification forming part of Letters Patent No. 118,169, dated August 15, 1871.

To all whom it may concern:

Be it known that we, GEORGE W. TINSLEY and EBENEZER W. STORER, of Minneapolis, in the county of Hennepin and State of Minnesota, have invented certain new and useful Improvement in Molds for Finger-Rings; and we do hereby declare that the following is a full, clear, and exact description thereof, reference being had to the accompanying drawing and to the letters of reference marked thereon which form a part of this specification.

The nature of our invention consists in the construction and arrangement of a mold for casting finger-rings, as will be hereinafter more fully set forth.

In order to enable others skilled in the art to which our invention appertains to make and use the same, we will now proceed to describe its construction and operation, referring to the annexed drawing, in which—

Figure 1 is a longitudinal vertical section of the entire mold. Fig. 2 is a plan view of the lower half of the flask or mold. Fig. 3 is a bottom view of the upper half, and Fig. 4 is an end view of the core.

A A' represent the halves of a metal flask or mold, having each a central circular hole, a or a'. In the lower half A are two upwardly-projecting pins, b b, which fit into corresponding holes b' b' in the upper half A'. Around the upper edge of

the central hole a in the lower half A is a recess, d, and around the lower edge of the hole a' in the upper half A' is a similar recess, d', the two when put together forming a circular cavity for a ring. From these recesses in each of the halves A A' lead a semi-tubular groove, e and e', to the edge of the flask or mold, the outer ends of said grooves being enlarged so as to form a funnel-shaped opening, f, into which the metal is poured. In the central opening a a' is inserted a tubular core, B, made of sheet metal or other suitable material, the edges of which overlap each other without being fastened together. This core is thus made yielding so as to allow for the shrinking of the metal.

Having thus fully described our invention, what we claim as new, and desire to secure by Letters Patent, is—

The yielding core B, made of metal or other suitable material, in combination with a flask or mold, A A', for finger-rings, all constructed and arranged substantially as and for the purposes herein set forth.

In testimony that we claim the foregoing as our own we affix our signatures in presence of two witnesses.

G. W. TINSLEY.
E. W. STORER.
